No. 779,349.

PATENTED JAN. 3, 1905.

G. H. COLLIER.

ENGINE.

APPLICATION FILED AUG. 24, 1904.

FIG 1

FIG 2

UNITED STATES PATENT OFFICE.

GEORGE HERBERT COLLIER, OF JOPLIN, MISSOURI.

ENGINE.

SPECIFICATION forming part of Letters Patent No. 779,349, dated January 3, 1905.

Application filed August 24, 1904. Serial No. 221,978.

To all whom it may concern:

Be it known that I, GEORGE HERBERT COLLIER, a citizen of the United States, and a resident of Joplin, in the county of Jasper and State of Missouri, have invented a new and Improved Engine, of which the following is a full, clear, and exact description.

The invention relates to a steam-engine having an oscillating piston arranged in a suitable chest or cylinder and joined by a connecting-rod with a crank-shaft, so as to rotate the shaft upon the oscillation of the piston. The chest or cylinder is provided with feed and exhaust ports controlled by a slide or other valve driven from eccentrics on the crank-shaft.

The invention actually consists in certain peculiar features of construction and the relative arrangement of parts, which will be fully set forth hereinafter and then pointed out in the claim.

Reference is had to the accompanying drawing, showing as an example the preferred embodiment of the invention, in which like characters of reference indicate corresponding parts in both views, and in which—

Figure 1 is a sectional elevation taken through one of the cylinders on essentially the line 1 1 of Fig. 2, and Fig. 2 is a front elevation of the engine.

As shown in Fig. 2, the type of engine here illustrated is provided with two cylinders 10, which, as illustrated in Fig. 1, are essentially segmental in cross-sectional form and through which a shaft 11 extends. These two cylinders are divided from each other, and in each is located a flat piston 12, having a hub 14 turning freely on the shaft 11, so that the pistons may oscillate back and forth in the cylinders around the centers of said shafts. The edges of the pistons and the hubs thereof are provided with suitable packings to make steam-tight connections between the parts.

The cylinders 10 are supported on a suitable bed 15, and on this bed a crank-shaft 16 is also carried. The cranks of this shaft are quartered on the shaft, and to said cranks are joined connecting-rod 17, which extend through openings 18 in the cylinders upward

into connection with the under sides of the 50 pistons, as illustrated. Mounted on top of the cylinders are steam-chests 19, in which feed-pipes 20 extend. In the cylinders are formed feed-ports 21 and exhaust-ports 22, both of these ports communicating with the 55 steam-chests and the former ports communicating with the respective cylinders, while the latter ports communicate with an exhaust-pipe 23. (Best shown in Fig. 2.) Slide or other valves 24 command the ports 21 and 22, and the stems 25 of said valves are connected to crank-arms 26 on a valve-shaft 27, mounted, preferably, on top of the engine, as shown, and having cranks 28 at their ends, to which crank-rods 29 are attached. The rods 29 extend downward to eccentrics 30 on the shaft 16, and in this manner a rocking movement is imparted to the shaft 27, and from this shaft the slide-valves are operated characteristic- 70

The valves 24 being properly adjusted a portion of the engine is started when steam is supplied to the chests. The ports 21 will be uncovered to allow the steam to pass into the cylinders, thus throwing down the pistons. As the pistons begin their return movement the ports 21 and 22 are placed in communication, and the steam is exhausted out through the pipe 24. Any number of cylinders may be employed together in this manner, and the engine so constructed makes an extremely simple yet powerful apparatus. 75

Various changes in the form, proportions, and minor details of my invention may be resorted to at will without departing from the 80 spirit and scope thereof. Hence I consider myself entitled to all such variations as may lie within the intent of my claim.

Having thus described my invention, I claim as new and desire to secure by Letters Patent— 90

An engine having an essentially segmental cylinder, a shaft extending along the axis thereof, a piston mounted to swing on the shaft within the cylinder, a crank-shaft, a connection between the crank-shaft and piston, a steam-chest mounted on the cylinder, the cylinder having feed and exhaust ports, the one leading between the steam-chest and the in- 95

terior of the cylinder, and the other leading from the steam-chest to the atmosphere, a valve controlling said parts, a stem connected to the valve, a rock-shaft mounted on the cylinder, a connection between the rock-shaft and stem, and means for driving the rock-shaft from the crank-shaft.

In testimony whereof I have signed my name to this specification in the presence of two subscribing witnesses.

GEORGE HERBERT COLLIER.
